(57) **CLAIM**

The ornamental design for a car adapter, as shown and described.

DESCRIPTION

FIG. 1 is a front perspective view of the car adapter according to the present invention.

FIG. 2 is a front view of the car adapter device according to the present invention.

FIG. 3 is a rear view of the car adapter of FIG. 1.

FIG. 4 is a right side view of the car adapter of FIG. 1.

FIG. 5 is a left side view of the car adapter of FIG. 1.

FIG. 6 is a top view of the car adapter of FIG. 1.

FIG. 7 is a bottom view of the car adapter of FIG. 1.

FIG. 8 is a side view of the car adapter of FIG. 4 in an alternate position; and,

FIG. 9 is a side view of the car adapter of FIG. 4 in another alternate position.

Portions shown in dashed lines from no part of the claimed design.
